UNITED STATES PATENT OFFICE.

RAYMOND W. GRIFFITH, OF MILWAUKEE, WISCONSIN.

COMBINATION-LOCK.

1,353,583.

Specification of Letters Patent. Patented Sept. 21, 1920.

Application filed August 4, 1919. Serial No. 315,207.

To all whom it may concern:

Be it known that I, RAYMOND W. GRIFFITH, a citizen of the United States, and resident of Milwaukee, in the county of Milwaukee and State of Wisconsin, have invented new and useful Improvements in Combination-Locks, of which the following is a description, reference being had to the accompanying drawings, which are a part 10 of this specification.

The invention relates to combination locks.

One of the objects of this invention is to produce a lock in which it is necessary to turn one or more tumblers to a predetermined position before the lock can be operated but in which it is not possible for one to get the "feel" of the tumblers due to another interlocking connection.

The invention further consists in the several features hereinafter set forth and more particularly defined by claims at the conclusion hereof.

In the drawings: Figure 1 is a vertical sectional view through the device embodying the invention; Fig. 2 is a side elevation view thereof, parts being broken away; Fig. 3 is a top view of the device; Fig. 4 is a section taken on the line 4—4 of Fig. 1; Fig. 5 is a section taken on the line 5—5 of Fig. 1; Fig. 6 is a top view of the key ring; Fig. 7 is a section taken through the core on the line 7—7 of Fig. 1; Fig. 8 is a section through the core taken on the line 8—8 of Fig. 1; Fig. 9 is a detail view of the thrust 30 washer.

In general the lock consists of two members 10 and 11, having relative rotary movement with respect to each other and adapted to be interlocked against longitudinal movement with respect to each other except in a predetermined position and one or more tumblers 12 which prevent the longitudinal movement of said members with respect to each other except in a predetermined position.

The member 10 is here shown as the fixed element of the lock, being made up of two complementary, semi-cylindrical, hollow sections secured together by screws 13 and having flange portions 14 to which an outer casing 14' is secured. This member is provided with annular grooves 15 in which circular disks forming the tumblers 12 are mounted and free to be turned therein, 55 though preferably normally held against

turning movement by springs 16 seated in longitudinal slots 17 in said member and bearing on the peripheries of the disks. The member 10 also has an annular groove 18 therein in which a circular thrust washer 60 and guide disk 19 is mounted. This member has a cap 20 tightly fitting thereon and forming what will be termed a "key ring" provided with an inwardly projecting flange portion extending over the top end of the 65 bore 21 and having a plurality of notches 22 formed by notching said flange portion.

The member 11 is here shown as the movable element of the lock and consists of a cylindrical portion or shank 23 provided with a key 24, a cylindrical portion or core 25 of larger diameter than the portion 23, a stem 26 and a handle or knob 27. A cylindrical cover 28 and a member 29 having locating spring fingers 30 are mounted on the 70 stem, being held in position by a coiled spring 31 on the stem interposed between the member 29 and the portion 25. The core 25 is provided with a plurality of longitudinally extending grooves 32 of unequal 80 placing and which are adapted to be brought into register with the projections 22 on the key ring so that the member 11 may be moved longitudinally of the member 10. Said member 11 also has short grooves or 85 shallow pockets 33 in its top which permit a slight longitudinal movement of the member with respect to the member 10 but prevent actuation of the lock and serve as "blinds" to prevent picking the lock as they do not permit the movement of the upper 90 end of the member 11 through the key ring and this can only be accomplished when the grooves 32 are brought into register with the proper projections on the key ring. Thus 95 while the member 11 may be turned with respect to the member 10, said members are interlocked against relative longitudinal movement with respect to each other sufficient for unlocking until said members are 100 brought to a predetermined position.

The tumblers 12 are each provided with a pin 34 on one side and a pin 35 on the other side thereof, a central opening 36 clearing the key 24 and a notch 37. While 105 one tumbler may be used with a single pin, the number of possible combinations of the lock is greatly increased by using two or more tumblers and two pins on each tumbler.

The thrust washer 19 is provided with a keyway 38 in which the key 24 slides and a notch 39 to permit one or more of radially disposed pins 40 on the portion 23 to pass through said washer. This washer 19 limits the inward movement of the member 11 and serves as a guide disk turning with the shank 23. These pins 40 also coöperate with the pins 34 and 35 so as to rotate the tumblers to a predetermined position to set the tumblers so that the pins 40 may pass through the notches 37 to permit the desired longitudinal movement of the member 11 with respect to the member 10.

When pins are used on both sides of the disk it is necessary to provide a limited longitudinal movement of the member 11 with respect to the member 10 and this is accommodated by making the length of the bore 21 in which the core 25 is mounted longer than said portion and when member 11 reaches the end of this limited movement the spring fingers 30 engage in recesses 41 in the outside of the member 10, the sides 42 of said member adjacent the recesses being flat so that the flat springs engage them as the member 11 is turned. The relation of the finger or fingers 30 to the grooves 32 is such as to locate the grooves in the same position circumferentially as are the projections 22 of the key ring 20 when said finger or fingers 30 are engaging the flat sides or seats 42 of the member 11.

In order to completely disconnect or separate the members 10 and 11 when desired, the core 25 of the member 11 has a transverse slot 43 formed therein and longitudinal slots 44 communicating with said slot 43 and arranged and spaced similar to the grooves 32 but out of line therewith. Thus when the member 11 is unlocked and moved lengthwise until the projections on the key ring reach the end of the grooves 32, then a slight turning of the member 11 brings the teeth of said ring into register with the slots 44 and then a further lengthwise movement of the member 11 permits a withdrawal of the member 11 from the member 10.

The device may be mounted in any suitable manner and I have here shown the casting 14' provided with a flange 45 and one or more clamps as the clamp 46 in Fig. 1 is or are connected to the bolt or bolts 47 so that the supporting plate 48 may be clamped between the flange 45 and the clamp 46 or several similar clamps. The lower end of the member 10 is provided with a cap 49 secured to it by a removable pin 50.

Fig. 1 of the drawing shows the lock as the parts would appear in locked position. When in unlocked position the member 11 with its parts has been moved to bring the projections 22 of the key ring 20 at the ends of the grooves 32. The core 25 of the member 11 is free to slide and rotate so long as

it is within the confines of the disk 19 and the key ring 20 and has within this space a small amount of longitudinal travel in proportion to the amount available when said lock is in the unlocked position. This limited movement is provided so as to permit the shifting of the pins 40 on the shank 23 into engagement with the different pins 34 and 35 on the tumblers. If a single tumbler and pin is used this movement is not necessary. The core 25 when moved to a position to bring the grooves 32 in line with the proper projections on the key ring may be moved longitudinally to unlocked position provided the other parts of the lock, that is: the tumblers 12 and the position of the pins 40 with respect thereto, are in a position to allow it.

In rotating the core 25 the pins 40 engage the pins 34 or 35 in the disks or tumblers 12 which in turn rotate with it. When the core 25 is adjacent the guide disk 19 the pins 40 engage the pins 34 or the pins which extend toward said disk. When the core 25 is moved away from the disk 19 the pins 40 engage the pins 35 or those pins extending away from said disk. Thus the disks may be rotated by the pins extending from either side as may be necessary for the correct operation of the lock. The pins on the tumblers are so located that only one on each tumbler can possibly place the slot in said tumbler in correct position to permit passage of the pin on the shank 23 therethrough. After the tumblers have been set, then a partial turn of the member 11 to the proper position for sliding movement of the core in the key ring puts the parts in a position to be unlocked. The key ring prevents setting the tumblers by "feeling" for the notches therein.

The handle 27 has a notch 51 therein to assist in setting the combination. The lock above described may be used in connection with any part to be held against actuation until the longitudinal movement of the movable element has been effected.

To unlock the lock, the operator gives the handle 27 a complete turn, thus picking up all the tumblers, and stops with the notch 51 in a predetermined position. He then rotates the member 11 so that pin 40 striking pin 34 on the lower tumbler 12 carries said tumbler around to the predetermined position, which is known to him by the position of the notch 51, and by a reverse rotation of the member 11 the upper tumbler 12 in a similar manner is given a predetermined position by the movement of the pin 40 against the pin 34. Thus both tumblers have been given a preliminary setting. The operator then draws up on the member 11 until the fingers 30 engage in the notches 41 at which time the pins 35 on the tumblers come into the path of the pins 40 on the

shank 23 when said member 11 is rotated. The operator then turns member 11 until the pin 40 engaging the pin 35 on the lower tumbler has turned it from its preliminary 5 setting to "unlocked" position, and by a reverse rotation of the member 11, the upper tumbler 12 is similarly moved from its preliminary setting to "unlocking" position. After the tumblers have been moved in this 10 manner a partial turn of the member 11, so as to bring the grooves 32 into position to pass through the key ring 22, permits the member 11 to be moved longitudinally to "unlocked" position, that is, the pins 40 may 15 pass through the slots 37 in the tumblers 12, and the projections 22 through the grooves 32, this extended longitudinal movement of the member 11 being used to unlock any parts to which the above device may be 20 connected.

While I have shown and described the element 11 as being the movable member it will be understood that the member 10 can be made the movable element and be provided with suitable means such as the pins 40 for turning the tumblers with respect to the fixed element and that the key ring may then be mounted on the member 11 and cooperate with grooves in the member 10 similar 25 to the grooves 32; in other words, the position of the parts may be reversed so that the element 11 becomes the fixed element and element 10 the movable element. I am also aware that other changes in construction 30 may be effected within the spirit of the invention and I therefore desire it to be understood that this invention is not limited to any specific form or arrangement of parts except in so far as such limitations are specified 35 in the claims.

What I claim as my invention is:

1. In a combination lock, the combination of two elements relatively rotatable with respect to each other and having an interlocking connection to prevent longitudinal movement of the elements with respect to each other except in a predetermined position, and a third element freely rotatable with respect to the first named elements and 45 adapted to be turned by one of them and preventing the longitudinal movement of said elements with respect to each other to an unlocked position except in a predetermined position.

2. In a combination lock, the combination of two elements relatively rotatable with respect to each other and having an interlocking connection allowing a limited longitudinal movement of one of the elements 50 with respect to the other but preventing longitudinal movement to unlocked position except in a predetermined position, and a third element freely rotatable with respect to the first named elements and adapted to be turned by one of them when in different 55

longitudinal positions and preventing longitudinal movement of said first named elements to an unlocked position except in a predetermined position.

3. In a combination lock, the combination 70 of a pair of coaxially disposed elements relatively rotatable with respect to each other and having an interlocking connection to prevent longitudinal movement of the elements with respect to each other to an unlocked position except in a predetermined position, and a third element mounted between and rotatable about the axis of the first named elements and adapted to be turned by one of them, said third element 80 preventing the longitudinal movement of said first named members with respect to each other to an unlocked position until turned to a predetermined position.

4. In a combination lock, the combination 85 of a pair of elements relatively movable with respect to each other, one of the elements being free to rotate with respect to the other in "locked" position, an interlocking connection between said elements preventing longitudinal movement of the rotating element until turned to unlocked position, a tumbler free to turn with respect to said elements and preventing unlocking thereof until said elements have been moved to a 90 predetermined position, and means on the rotating elements for turning the tumbler to a position in which a part of said element engaged by the tumbler may be passed through said tumbler. 100

5. In a combination lock, the combination 105 of a pair of coaxially disposed elements, one of the elements being free to rotate and having a limited longitudinal movement with respect to the other in "locked" position, an interlocking connection between said elements preventing further longitudinal movement of the rotating element until turned to "unlocked" position, a tumbler free to turn with respect to said elements and preventing unlocking thereof until said elements have been moved to a predetermined position, and means on the rotating element engaging the tumbler in different longitudinal 110 positions for turning the tumbler to a position in which said element may be disengaged from the tumbler. 115

6. In a combination lock, the combination 120 of an element having a part provided with projections, another element having a part provided with longitudinally extending grooves, said elements being coaxially mounted and one having relative rotary movement with respect to the other to bring the projections and grooves into line so that 125 the movable element may be moved longitudinally with respect to the other element to "unlocked" position, a third element locking said first named elements against longitudinal movement to "un- 130

locked" position, and means on the movable element for turning said third element to a position for "unlocking."

7. In a combination lock, the combination 5 of a cylindrical casing forming a lock element, a member fitting within said casing and forming another lock element, said elements having relative rotary movement with respect to each other in "locked" position, 10 an interlocking connection between said elements to prevent longitudinal movement thereof with respect to each other to "unlocked" position except in a predetermined position, a tumbler free to rotate between 15 said elements and normally preventing "unlocking" of the first named elements, and means on one of the elements engaging the tumbler to turn it to a position for "unlocking."
- 20 8. In a combination lock, the combination of a cylindrical casing forming a lock element, a member fitting within said casing and forming another lock element, said elements being connected together to have relative rotary movement and a limited longitudinal movement with respect to each other in "locked" position and a further longitudinal movement when in a predetermined position to "unlocked" position, and a plurality 25 of tumblers free to rotate between said elements and normally preventing "unlocking" thereof, and means on one of the elements selectively engaging the tumblers to turn them to a position for unlocking.
- 30 9. In a combination lock, the combination of a relatively fixed element, a movable element, said elements being coaxially disposed and having an interlocking connection against "unlocking" except when the 35 movable element is turned to a predetermined position with respect to the fixed element, locating spring fingers carried by the movable element, a tumbler free to rotate between said elements and preventing "unlocking" 40 thereof except when turned to a predetermined position, and means on the movable element engaging the tumbler to turn the same to a position for unlocking.
- 45 10. In a combination lock, the combination

of a relatively fixed element, a movable element, said elements being coaxially disposed and having an interlocking connection against movement longitudinally to "unlocked" position except when the movable element is turned to a predetermined position, a plurality of tumblers free to rotate between said elements and preventing unlocking thereof except when turned to a predetermined position and provided with pins on opposite sides thereof, and pins on the 60 movable element selectively engageable with the pins on the tumblers to turn the same to a position for "unlocking."

11. In a combination lock, the combination 65 of a lock element provided with projections, an element having longitudinally extending recesses of unequal length and spacing, said elements being rotatable with respect to each other and one of the elements being longitudinally movable to "unlocked" position 70 when certain of the grooves of the one element are in register with the projections on the other element, and a third element freely rotatable with respect to the first named elements and adapted to be turned 75 by one of them and preventing longitudinal movement of said elements with respect to each other to unlocked position except in a predetermined position.

12. In a combination lock, the combination 80 of a fixed lock element, a movable lock element rotatable with respect to the fixed element and having an interlocking connection therewith to prevent its longitudinal movement with respect thereto to "unlocked" 85 position except in a predetermined position, a third element freely rotatable with respect to the first named elements, and having an interlocking connection with the movable element to prevent longitudinal movement 90 thereof to unlocked position except in a predetermined position.

In testimony whereof, I affix my signature, in presence of a witness.

RAYMOND W. GRIFFITH.
